UNITED STATES PATENT OFFICE.

CHARLES S. MCCARTHY, OF TOLEDO, OHIO.

VEHICULAR TOY.

Application filed November 5, 1926. Serial No. 146,414.

This invention relates to a vehicular toy, and particularly to manually propelled bodies of this character such as are generally known as skipmobiles or coaster wagons.

5 In this type of vehicles, it has been customary to propel the same by one foot, as the other rests upon a foot support carried by the frame of the toy device. Ordinarily no power means, other than the manual effort 10 of the boy or girl operating the toy, is relied upon; hence the desirability of some kind of motor of a most simple nature to apply additional propelling power. This is obtained by the invention herein set forth.

15 The present invention therefore involves an exceedingly simple and effective power device comprising a power spring actuated through the rotative movement of the propelling wheels of the vehicle so that in the 20 ordinary propulsion thereof on a level or descending grade, power is conserved or stored in the spring and adapted to be automatically utilized for continued propulsion or when there is an increased resistance, as 25 in the case of an ascending grade.

In such a toy it is also important to provide for operation of the vehicle independent of the power means which is not possible in prior constructions so far as I am 30 aware, and further to provide an automatic disconnection for the spring tension when it has reached a degree proper for application in its retractive action to the propelling wheel for driving purposes.

35 It has also been found practically necessary to provide a simple and efficient construction which can be readily applied to the ordinary character of toy vehicles and in which the drive shaft is constantly geared 40 with the propelling wheel by an interposed one-way clutch and the spring tensioning gears carried by such wheel adapted to be manually shifted into driving relation but automatically released therefrom by the action 45 of the spring when under driving tension.

The invention has for an object to provide a novel and improved construction of propelling means for a vehicular toy comprising 50 a driving shaft geared to a propelling wheel and having a power spring tensioned by intermittent connection with said wheel, with means for automatically releasing the tensioning connection for the spring and applying the retractive action thereon for driving purposes.

A further object of the invention is to provide a new construction of vehicle in which the propelling wheel is geared to a drive shaft having a power spring connected thereto, with manually controlled means for connecting this shaft with the wheel for rotation in one direction to tension the spring and automatic means to release the manually controlled means and permit rotation 65 of the shaft in an opposite direction by the tension of said spring to drive the propelling wheel.

Another object of the invention is to provide an improved construction wherein the 70 propelling wheel of the vehicle is provided with concentric gears one of which is connected with a drive shaft through a one-way clutch, said shaft carrying a power spring and a shiftable gear adapted to engage a 75 second gear on the wheel for the purpose of tensioning said spring, together with means for shifting the latter gear and retaining it in its adjusted position.

Other and further objects and advantages 80 of the invention will be hereinafter set forth and the novel features thereof defined by the appended claims.

In the accompanying drawings:

Figure 1 is a side elevation showing the 85 invention applied;

Figure 2 is a vertical section with parts broken away;

Figure 3 is a detail elevation of the propelling wheel and its connecting gears; 90

Figure 4 is a plan view thereof with parts in section;

Figure 5 is a section on the line 5—5 of 95 Figure 3;

Figure 6 is a similar view on the line 6—6 of Figure 3;

Figure 7 is a detail section on the line 7—7 of Figure 4; and

Figure 8 is a like view on the line 8—8 of Figure 3. 100

Like reference numerals designate corresponding parts throughout the several figures of the drawing.

The invention is designed for application not only to the usual type of toy scooters but 105 also to coaster wagons and like vehicles adapted to be manually propelled generally by children. For the purpose of illustration, however, it is shown in connection with a skipmobile in which the frame 10 is provided at its forward end with the usual pivoted steering post 11 having handles 12

and wheel 13. The rearward portion of this frame is composed of the parallel members 10 intermediate of which the propelling wheel 14 is pivotally mounted upon the axle 15 in the ordinary manner. This wheel has secured thereto any desired character of driving gear 16 which in the present instance is formed with a gear face 17 for propelling purposes and a concentric inner gear face 18 for tensioning purposes.

The frame 10 of the vehicle has secured thereto at its rear a bracket 19 carrying a bearing 20 for the end of the shaft 21 and a substantially similar bracket 22 is provided at a forward point on the frame and carries a bearing 23 for the front end of the shaft 21. This shaft has mounted thereon adjacent the bearing 20 a bevel gear 24 which is secured in contact with the bearing 20 by a pin and washer as indicated at 25. This gear 24 is interiorly formed with a one-way clutch of any preferred construction, for instance a key 26 slidably mounted in a slot 27 extending diametrically of the shaft 21 and adapted to engage in the recessed seats 28 within the hub of the gear as usual in this type of clutch. Such mounting permits the free rotation of the gear on the shaft in one direction and a driving connection therewith in an opposite direction of rotation.

The shaft 21 is surrounded by a driving or power spring 30 which is secured thereto at one end by the means shown at 31 and the opposite end of said spring is connected at 32 with a sleeve 33 slidably mounted upon the shaft, and held against rotation by arm 49 operating in slot 50 in a plate 45. The shaft also has slidably keyed thereon a bevelled pinion or gear 34 which is intermittently brought into mesh with the inner tensioning gear 18 upon the propelling wheel. The collar 35 from the gear 34 is provided with a circumferential groove 36 adapted to receive a pin 37 from the arm 38 of the shifting lever 39 which is pivotally mounted upon the vehicle frame 10 at 40 at opposite sides of the frame and tensioned in one direction by a spring 41 extending from the lever 39 to a post 42 from the frame. The lever 39 is also provided with a depending dog or latch 43 pivoted at 44 thereon and connected with a depending plate 45 from the frame by a spring 46. The latch 43 is tensioned by the spring 46 toward a lug 47 on the plate 45 which engages with a seat 48 on the latch to prevent vertical movement thereof after manual depression to throw the tensioning gear into operative relation with the propelling wheel. The opposite face of the latch is formed with a seat 56 cooperating with a stop 57 to limit the releasing movement of the latch and determine accurately the position of the gear 34 upon the shaft. Under this condition the

spring is placed under tension and such action results in an elongation of the spring bodily and a reduction in the diameter of the coils thereof, with the result that the arm 49 from the collar 33 travels in the slot 50 of the plate 45 and when this spring has received its full tension engages the latch 43 to release the same from the lug 47 and permit its upward movement by the spring 41 which retracts the tensioning gear 34 from its driving relation to the propelling wheel. At this time the spring is free to act through its retractive power and reverses the direction of rotation of the shaft 21 so that the driving gear 24 thereon applies power to the propelling wheel through the outer gear 17 with which it is in constant mesh.

In the mounting of the propelling means upon the vehicle it is desirable to protect them and also the user of the vehicle which is desirably effected by means of the top plate 51 having a curved depending extension 52 at one side which substantially encloses the driving shaft and its spring. This plate may also be provided with a tread 53 of rubber or any desired material. A rear casing 58 may be used to enclose the gearing.

The rear of the frame 10 may also be provided with the usual type of rest 54 pivoted thereto at 55 and adapted to be swung beneath the wheel to support the vehicle when at rest and to lie in a raised position as shown in Figure 1 when it is in use.

The operation of the invention will be apparent from the foregoing description from which it will be seen that it is only necessary for the user to depress the shift lever from the full line position in Figure 3 to that indicated by dotted lines in order to apply tension to the driving spring and during such application of tension the driving gear upon the shaft through its clutch connection runs idle. When the spring has received its proper tension the shift lever is automatically released and restored so as to withdraw the tensioning gear from the propelling wheel and permit the application of power through a reversed rotation of the driving shaft. It will therefore be seen that the invention only requires the forward pushing movement of the operator for the purpose of storing the power in the spring when running upon a level or descending grade and if it is not desired to use this power the parts are operable independent thereof so long as the shift lever is not depressed.

The construction presented is simple, efficient and economically manufactured so as to be readily adapted for application to vehicles of the ordinary type for the purpose of application of power thereto with a minimum of effort and the utmost simplicity in operation.

While the details of the invention have

been specifically shown and described, it is not confined thereto as changes and alterations may be made without departing from the spirit of the invention as defined by the following claims.

Having thus described my invention, what I claim as new and desire to secure by Letters Patent is:

1. A propelling means for a vehicular toy comprising a frame having a ground wheel, a drive shaft geared thereto, a driving spring connected to said shaft, means adapted to be driven by the wheel for tensioning said spring, and means actuated by the bodily movement of the toy for shifting said tensioning means to permit retractive action of the spring upon the wheel.

2. A propelling means for a vehicular toy comprising a wheel, a drive shaft geared thereto, a driving spring connected to said shaft, means adapted to be driven by the wheel for tensioning said spring, and means for automatically shifting said tensioning means out of driving relation with said wheel to permit retractive action of the spring thereon.

3. A propelling means for a vehicular toy comprising a wheel, a drive shaft geared thereto, a driving spring connected to said shaft, means adapted to be driven by the wheel for tensioning said spring, means for shifting said tensioning means to permit retractive action of the spring upon the wheel, and means for retaining the shifting lever in driving relation.

4. In a propelling means for a vehicular toy, a frame, a wheel mounted therein and carrying gears, a driving shaft having a gear mounted thereon with a one-way clutch, a tension spring connected to said shaft, a gear slidably keyed upon the shaft to engage one of the wheel gears, and means for shifting said last mentioned gear into and out of operative relation.

5. In a propelling means for a vehicular toy, a frame, a wheel mounted therein and carrying gears, a driving shaft having a gear mounted thereon with a one-way clutch, a tension spring connected to said shaft, a gear slidably keyed upon the shaft to engage one of the wheel gears, a lever adapted to manually shift said sliding gear into operative relation, and means for automatically releasing said sliding gear when the spring is under tension.

6. In a propelling means for a vehicular toy, a frame, a wheel mounted therein and carrying gears, a driving shaft having a gear mounted thereon with a one-way clutch, a tension spring connected to said shaft, a gear slidably keyed upon the shaft to engage one of the wheel gears, a lever adapted to manually shift said sliding gear into operative relation, and means controlled by the tension of the spring for releasing the

shifting lever for automatic movement of the sliding gear out of operative relation with the wheel.

7. In a propelling means for a vehicular toy, a frame, a wheel mounted therein and carrying gears, a driving shaft having a gear mounted thereon with a one-way clutch, a tension spring connected to said shaft, a gear slidably keyed upon the shaft to engage one of the wheel gears, a lever adapted to manually shift said sliding gear into operative relation, means controlled by the tension of the spring for releasing the shifting lever for automatic movement of the sliding gear out of operative relation with the wheel, and a latch carried by said lever for retaining the sliding gear in operative relation during the tensioning of the spring.

8. In a propelling means for a vehicular toy, a frame, a wheel mounted therein and carrying gears, a driving shaft having a gear mounted thereon with a one-way clutch, a tension spring connected to said shaft, a gear slidably keyed upon the shaft to engage one of the wheel gears, a lever adapted to manually shift said sliding gear into operative relation, means controlled by the tension of the spring for releasing the shifting lever for automatic movement of the sliding gear out of operative relation with the wheel, a latch carried by said lever for retaining the sliding gear in operative relation during the tension of the spring, and a stop cooperating with said latch to limit its releasing movement.

9. A propelling means for a vehicular toy comprising a frame, a wheel mounted therein and provided with concentric gears, a drive shaft, a pinion thereon meshing with one of said gears and having a one-way clutch relation to said shaft, a tensioning gear slidably mounted upon the shaft to engage the other wheel gear, a power spring secured to said shaft, and means for shifting said tensioning gear relative to the wheel gear.

10. A propelling means for a vehicular toy comprising a frame, a wheel mounted therein and provided with concentric gears, a drive shaft, a pinion thereon meshing with one of said gears and having a one-way clutch relation to said shaft, a tensioning gear slidably mounted upon the shaft to engage the other wheel gear, a power spring secured to said shaft, means for shifting said tensioning gear relative to the wheel gear, and a sliding collar connected to the spring and mounted upon said shaft to automatically release the shifting means when the spring is under tension.

11. A propelling means for a vehicular toy comprising a frame, a wheel mounted thereon, a drive shaft, means for gearing said shaft in driving relation to the wheel, a coiled power spring secured at one end to

said shaft and at its opposite end to a collar slidably mounted thereon, shiftable means for rotating said shaft to tension said spring, and means controlled in the tensioning action of the spring to release the tensioning means.

12. A propelling means for a vehicular toy comprising a frame, a wheel mounted thereon, a drive shaft, means for gearing said shaft in driving relation to the wheel, a coiled power spring secured at one end to said shaft and at its opposite end to a collar slidably mounted thereon, shiftable means for rotating said shaft to tension said spring, means controlled in the tensioning action of the spring to release the tensioning means, and latching means for retaining the tensioning means in operative relation and disposed to be released in the movement of the collar carried by the tensioning spring.

13. A propelling means comprising a frame, a wheel mounted therein provided with a tensioning gear, a driving shaft upon which said gear is slidably keyed, a coiled spring surrounding said shaft and secured thereto at one end, a shift lever mounted upon the frame and pivotally connected with said gear, means for restoring said shift lever to elevated position, and latching means for retaining said shift lever when depressed.

14. A propelling means comprising a frame, a wheel mounted therein provided with a tensioning gear, a driving shaft upon which said gear is slidably keyed, a coiled spring surrounding said shaft and secured thereto at one end, a shift lever mounted upon the frame and pivotally connected with said gear, means for restoring said shift lever to elevated position, and a latch pivotally depending from the shift lever and adapted to engage a fixed lug for retaining the lever in depressed position.

15. A propelling means comprising a frame, a wheel mounted therein provided with a tensioning gear, a driving shaft upon which said gear is slidably keyed, a coiled spring surrounding said shaft and secured thereto at one end, a shift lever mounted upon the frame and pivotally connected with said gear, means for restoring said shift lever to elevated position, a latch pivotally depending from the shift lever and adapted to engage a fixed lug for retaining the lever in depressed position, and a spring for tensioning said latch toward said lug.

16. A propelling means comprising a frame, a wheel mounted therein provided with a tensioning gear, a driving shaft upon which said gear is slidably keyed, a coiled spring surrounding said shaft and secured thereto at one end, a shift lever mounted upon the frame and pivotally connected with said gear, means for restoring said shift lever to elevated position, a latch pivotally de-

pending from the shift lever and adapted to engage a fixed lug for retaining the lever in depressed position, and a stop cooperating with the latch to limit its releasing movement.

17. In a vehicular toy, a frame, a propelling wheel mounted therein, a drive shaft provided with a clutched gear in mesh with a gear on said wheel, a power spring connected to said shaft, a gear thereon for tensioning said spring by driving contact with the wheel, and means controlled in the tensioning action of the spring for automatically releasing said tensioning gear.

18. In a vehicular toy, a frame, a propelling wheel mounted therein, a drive shaft provided with a clutched gear in mesh with a gear on said wheel, a power spring connected to said shaft, a gear thereon for tensioning said spring by driving contact with the wheel, means controlled in the tensioning action of the spring for automatically releasing said tensioning gear, means for shifting said tensioning gear into driving relation, and a retaining element for said shifting means disposed to be automatically released when said spring is placed under driving tension.

19. In a vehicular toy, a frame, a propelling wheel mounted therein, a driving shaft disposed in bearings at one side of said frame and geared to said wheel, a coiled spring surrounding said shaft, and a platform for said frame having a depending portion partially enclosing said shaft and spring.

20. In a vehicular toy, a frame, a propelling wheel mounted therein, a driving shaft disposed in bearings at one side of said frame and geared to said wheel, a coiled spring surrounding said shaft, a platform for said frame having a depending portion partially enclosing said shaft and spring, a tensioning gear for said spring, and a shifting lever therefor pivoted upon opposite sides of the frame and extending across the same.

21. A vehicular toy comprising a frame having propelling wheel and means for storing up power to drive said wheel, combined with an instrumentality to actuate the power storing means from the wheel in the bodily movement of the toy.

22. A toy as claimed in claim 21 comprising a foot support, and foot controlled means controlling the power storing means.

23. A toy as claimed in claim 21 having foot controlling means for the power storing means to initiate its power storing function, and automatic means to release and apply the power of the storing means to the wheel.

In testimony whereof I affix my signature.

CHARLES S. McCARTHY.
